Emery, Booth, Janney & Rooney

UNITED STATES PATENT OFFICE.

WALTER I. TUTTLE, OF PROVIDENCE, RHODE ISLAND, ASSIGNEE TO FRANK MOSSBERG
COMPANY, OF ATTLEBORO, MASSACHUSETTS, A CORPORATION OF RHODE ISLAND.

BRACE CONSTRUCTION.

1,335,408.

Specification of Letters Patent. Patented Mar. 30, 1920.

Application filed October 3, 1918. Serial No. 256,646.

To all whom it may concern:

Be it known that I, WALTER I. TUTTLE, a citizen of the United States, and a resident of Providence, in the county of Providence and State of Rhode Island, have invented an Improvement in Brace Construction, of which the following is a specification.

This invention relates to the construction of braces and the like, and more particularly to the end or thrust handles thereof. One of the objects thereof is to provide a construction of the above type of efficient action and strong, dependable structure. Another object is to provide a construction of the above type which shall be light in weight and cheap in manufacture. Other objects will be in part obvious and in part pointed out hereinafter.

The invention accordingly consists in the features of construction, combinations of elements and arrangements of parts which will be exemplified in the structure hereinafter described and the scope of the application of which will be indicated in the following claim.

In the accompanying drawing in which is shown one or more various possible embodiments of this invention,

Figure 1 is a side elevation cut away through the handle; and

Fig. 2 is a vertical section through the handle portion thereof, on an enlarged scale.

Similar reference characters refer to similar parts throughout the several views of the drawing.

Referring now to Fig. 1 of the drawing, there is shown a brace having crank portion 1 with end portions or members 2 and 3. It is to be understood that these end members may be formed integral or separate from the intermediate portions of the brace, and that the term "end member" is used broadly throughout.

Secured to end member 2 is the device which is operated by the brace, here shown as a socket member 4 to form a socket wrench. It is clear, however, that a chuck or other tool or tool-holding member might be employed at this point and many of the advantages of the invention achieved.

Referring now more particularly to the opposite end of the brace, especially as shown in Fig. 2 of the drawing, there is provided at the extreme end of the member 3 a beveled shoulder 5 which may be formed

by upsetting the metal. This shoulder fits within the corresponding recess or countersink 6 in a sheet metal member 7. The latter member is provided with a sleeve portion 8 embracing the member 3 and forming a bearing therewith. The member 7 is also provided with an outwardly directed curved flange 9 as shown in the drawing.

Fitted about the above parts is a member 10 also preferably formed of sheet metal and spun substantially into the shape indicated. This member conforms to and covers the outer extreme end of the member 3, and flange 9 of the member 7, and is thence curved along the brace and finally inwardly as indicated at 11. The edge of the member is preferably beveled as at 12 so as to avoid presenting a sharp edge to the fingers.

When the parts are assembled, the member 7, with the contained shank or end member of the brace, is secured, preferably by welding or riveting, at at 9^a, to the inner surface of the outer member 10 as indicated in the drawing.

The above construction forms what is termed the thrust handle as distinguished from a possible handle on the crank of the brace, and it is to be understood that this term "thrust handle" is broadly used throughout.

In the action of the device, the end member of the brace is securely locked into the handle and yet turns therein with perfect freedom. No rotating parts however are exposed to the hand of the user and thus any desired degree of pressure may be exerted without discomfort. The entire device is of light construction and correspondingly economical in metal, and is of low cost of manufacture. Its durability as well as convenience in use will be obvious.

It will thus be seen that there is provided a construction in which the objects of this invention and the above-noted as well as other advantages, gained.

As various possible embodiments might be made of the above invention and as various changes might be made in the embodiment above set forth, it is to be understood that all matter herein set forth or shown in the accompanying drawings is to be interpreted as illustrative and not in a limiting sense.

I claim as my invention:

In brace construction, a swiveled handle comprising in combination a hollow metal

handle member, a bearing member having a sleeve or bearing portion and an outwardly extending flange, and fitting and resting with its end surface against the inner surface of said handle member adjacent its central portion and secured thereto, said flange flaring outwardly from the sleeve portion to provide a circular recess adjacent said handle member, and a shank member having a

bearing in said sleeve portion and an end bearing against said handle member, and extending outwardly between said handle member and bearing member into said recess to lock itself in position.

In testimony whereof, I have signed my name to this specification this 17th day of September, 1918.

WALTER I. TUTTLE.
